(57) **CLAIM**

The ornamental design for a pallet lifter, as shown and described.

DESCRIPTION

FIG. 1 is a front perspective view of the pallet lifter in the non-raised position showing our new design;

FIG. 2 is a rear perspective view of the pallet lifter of FIG. 1 in the non-raised position;

FIG. 3 is a rear perspective view of the pallet lifter of FIG. 1 in the raised position;

FIG. 4 is a front perspective view of the pallet lifter of FIG. 1 in the raised position; and,

FIG. 5 is a front elevational view of the pallet lifter of FIG. 1 in the non-raised position.
